(57) CLAIM

The ornamental design for spray head for two container propellant-based liquid sprayer, as shown and described.

DESCRIPTION

FIG. 1 is a perspective view of this invention.

FIG. 2 is a top elevational view of this invention.

FIG. 3 is a left side view of this invention, the right side is mirror image thereof.

FIG. 4 is a rear view of this invention.

FIG. 5 is a front view thereof.

FIG. 6 is a bottom plan view of this invention; and,

FIG. 7 is a perspective view of this invention in its environment shown in dashed lines form no part of this design.
